UNITED STATES PATENT OFFICE.

LESLIE W. BEAVEN, OF CHICAGO, ILLINOIS.

MECHANISM FOR GRADING AGGREGATES.

1,368,422.

Specification of Letters Patent. Patented Feb. 15, 1921.

Application filed January 29, 1919. Serial No. 273,815.

To all whom it may concern:

Be it known that I, LESLIE W. BEAVEN, a citizen of the United States, and a resident of the city of Chicago, in the county of Cook and State of Illinois, have invented certain new and useful Improvements in Mechanisms for Grading Aggregates, of which the following is a specification.

10 Gravel and coarse and fine sand employed in building operations are generally found in nature commingled, and in order to obtain proper proportions of these respective materials for building operations, it is first necessary to grade or separate them so that 15 the desired proportions may be taken. At present, so far as I am aware, the grading of these materials involves the employment of a considerable amount of machinery and the action of the aggregates upon the screens 20 used for their grading or separation is exceedingly destructive to the machinery employed. Also the presence of moisture in the materials to be graded creates a considerable amount of cohesion between the particles 25 of the material which interferes with the grading operation unless the material has first been dried.

30 My present invention relates to the provision of apparatus for separating or grading aggregates, and has for its particular object the elimination of mechanical separating machinery; the lessening of the wear upon the grading machinery; and the elimination of cohesion between the particles of 35 the material to be graded, which would otherwise interfere with the grading operation. I prefer to attain the foregoing objects by means of the structure diagrammatically illustrated in the accompanying 40 drawings, in which,—

Figure 1 is a side elevation of a structure embodying my invention.

Fig. 2 is a longitudinal central section of the grading tank.

45 Fig. 3 is a transverse section taken on line 3—3, of Fig. 2.

Fig. 4 is a fragmental plan of the upper grading plate and its support.

50 Fig. 5 is a view similar to Fig. 4 of a modified form of grading screen.

Fig. 6 is a fragmental elevation of the shelf for supporting the grading elements.

Fig. 7 is a longitudinal section taken on line 7—7 of Fig. 2;

Fig. 8 is a longitudinal section taken on 55 line 8—8, of Fig. 2.

Fig. 9 is a detail view of a discharge head.

Fig. 10 is a fragmental detail of the end of a discharge pipe showing the gage for indicating the rate of discharge therefrom. 60

Fig. 11 is a fragmental view of the discharge end of the grading tank, as shown in Fig. 1, but with the discharge conduits arranged at a different angle or grade from that shown in Fig. 1 in order to control the 65 flow or discharge therethrough.

In the drawings similar reference characters are employed throughout the several views to designate the same parts.

The grading apparatus comprises a tank 70 or compartment 10, which I have shown as consisting of a spirally formed sheet metal pipe of approximately thirty (30') feet in length and of an inside diameter of forty (40") inches. Of course, these dimensions 75 may be either increased or diminished in accordance with the capacity of the apparatus which it is desired to construct, without in any way departing from the principles or mode of operation, and the form of 80 apparatus herein shown and described may also be altered without altering the mode of operation. Around both ends of this pipe are riveted rings 11 of angle metal so as to provide the annular flanges 12, which are 85 bored at suitable intervals for the passage of bolts 13 for securing the upper and lower heads, 14 and 15, respectively, to the open ends of said compartment. Secured diametrically opposite each other and approximately halfway between the top and bottom of the compartment, are longitudinally disposed strips of angle metal 16, 16, which extend from end to end of the compartment, substantially parallel to each other, and 90 have one flange of each piece of angle metal extending radially toward the center of the compartment to provide shelves 17. These shelves 17 are reinforced at suitable intervals with blocks of metal 18, that are secured to the under faces thereof by riveting, welding, sweating, or in any other suitable manner, and at the reinforced places the shelves and reinforcements are bored and 95 tapped to receive the threaded studs 19 that project above said shelves. A grading screen, preferably formed in sections, each section consisting of a plate 20 bored along

100

105

its longitudinal edges for the passage of the studs 19 and perforated throughout its central portion with holes 21, approximately three-eighths of an inch in diameter, to form 5 a reticulated or screening area, is supported upon the shelves 17 and secured thereto by nuts 22 which screw down upon the threaded studs 19.

Instead of employing the perforated 10 plates above described, such a screen as is shown in Fig. 5 may be employed. This screen, known as a "grisley" or "bar," consists of longitudinal parallel bars or rods 23, set the requisite distance apart, in this instance about three-eighths of an inch, and are provided with transverse braces 24, preferably electrically welded to the under sides of the longitudinal bars 23. This "grisley" or "bar" screen is preferably 15 mounted in a frame 25 of proper dimensions, which is bored at suitable intervals for the passage of the studs 19. Also other varieties of screening elements than herein described may be employed, if desired.

20 Preferably halfway between the shelves 17 and the bottom of the compartment, are provided similar shelves 26 that are formed of angle metal pieces 27, and in other respects are similar to the shelves 17. The 25 third of the shelves 26 adjacent the feed or inlet end of the compartment supports a frame 28 in which is mounted a screen 29 of metallic fabric, of a size known as 20-mesh, and the remaining two-thirds of the 30 shelving 26 carries unperforated metal plates 30 which, together with the frame and screen, 28 and 29, divide the space below the upper or coarse screen into two superposed passageways 31 and 32. The frame 35 28 and the plates 30 are secured upon the shelves 26 in a manner similar to that employed for securing the sections of the coarse screen 20 to the shelves 17. It should be noted that while I have described the 40 employment of a mesh extending approximately only one-third of the length of the lower shelves 26, a greater or less length of mesh may be employed according to whether it is desired that a greater or less proportion 45 of the finer or what is known as "bank sand" is to be removed from the coarse sand. It is also apparent that while I have described the employment of three passageways, the 50 number of passageways may be either increased or decreased without in any way modifying the method of operation, the 55 number of passageways being determined by the number of different grades into which it is desired to separate the aggregates.

60 The entire compartment or tank 10 is preferably inclined at an angle of substantially forty (40°) degrees to the horizontal, as illustrated in Fig. 1, and the upper end is closed by bolting thereto a head 14, in 65 the upper portion of which, above the up-

per coarse screen 20, is an inlet stub 34 adapted to be connected, through an elbow 35, with a pipe or conduit from a hydraulic dredging machine. The head 14 has riveted to its inner face two parallel strips 36 and 37 of angle metal, the outstanding flanges of which are adapted to extend just above the coarse screen 20 and the mesh frame 28, respectively.

To the lower end of the tank 10 is bolted 75 a closure 15, of the tapered or conical form shown in Fig. 9, terminating in the three discharge openings 39, 40, and 41, communicating, respectively, with the portion of the tank above the coarse screen, the passageway 31 between the screens, and the passageway 32 below the lower screen and unperforated plates. Secured to each of the discharge openings 39, 40, and 41, are lengths of pipe or conduit, 42, 43, and 44, which extend upwardly at substantially a forty-five (45°) degree angle to a point preferably above the horizontal plane of the highest interior point in the tank 10, and are then separated and extended to suitable places 80 for the deposition and storage of the graded materials. It, of course, will be appreciated that the rate of flow through the compartment 10, as well as the level of the fluid therein, can be controlled by either the 85 height to which the outlet conduits are carried or the amount of grade that is given to the outlet conduits, or the length to which the conduits are extended. In practice all 90 three of these conditions are utilized and, as 95 it is desirable to maintain the discharge from each outlet conduit at relatively the same head, I have provided means for ascertaining the rate of flow from the discharge ends of the conduits which are illustrated in Fig. 105 10 of the drawings. This means consists in securing to the end of each discharge conduit a flange nipple 47, provided with a lateral stub 48 into which a vertically disposed graduated glass tube 49 is secured by 110 means of the usual gland nut 50 and suitable packing. The height to which the water rises in the tube 49 will depend upon the 115 rate of flow from the outlet conduit and a comparison of a reading of the gages on the respective outlet conduits will immediately disclose the relation of the discharges from the several conduits. The closure 15 is preferably a casting of manganese or other hard steel, which is best adapted to withstand the 120 abrasion caused by the passage of the aggregates in transit therethrough.

From the highest part of the tank 10 extends an air-pipe 45 which is either carried above the highest point to which the head 125 employed in the system would carry the water, or is provided with an air-cock 46 by means of which air can be released from the interior of the tank.

In operating this device water is pumped 130

into the tank 10 through the inlet stub 34 until the air has been completely expelled and the tank is full and water flowing from the pipes 42, 43, and 44, then aggregates and water are permitted to enter. All material which cannot pass through the coarse screen is carried by the flow of water through the discharge opening 39 and the pipe 42 to the desired point for the receipt and storage of this grade of material. All of the aggregates which pass through the coarse screen and which do not pass through the 20-mesh screen are carried by the movement of the water through the discharge opening 40 and the pipe 43 to the proper point for its receipt and storage; and all of the finest material, which passes through the 20-mesh screen is carried by the movement of the water through the discharge opening 41 and the pipe 44 to the proper point for its receipt and storage.

It will be noted that the entire grading operation takes place under water where the material is lightened to the extent of the weight of the volume of water displaced thereby and where the cohesion created by moisture is entirely eliminated by the presence of an excess quantity of water. In this manner the grading or screening of the material is greatly facilitated and the wearing of the machinery is greatly reduced through the lightening of the materials and through the lubricating qualities of the water present. It should also be noted that the rate of travel of the materials, which is very important in the operation of grading, is controlled, primarily, by the relative cross-section of the securing tank and supply-pipe, and, secondarily, by the head or flow of water employed, and that the entire conveyance of the materials is accomplished without the use of any mechanical conveying mechanism except the dredge pipes and the water carried thereby.

While I have illustrated and described certain instrumentalities for carrying out my invention and have designated certain proportions and dimensions in connection therewith, it will be obvious to persons skilled in the art that divers changes and modifications may be made without affecting the principles involved. I therefore desire it understood that all such changes are contemplated as within the scope of the appended claims.

What I claim is:—

1. A grading mechanism comprising a compartment adapted to receive aggregates and water under pressure, said compartment being divided into superposed passageways, an inlet port located in the uppermost of said passageways, screening elements located in the division walls between said passageways, and separate outlet conduits leading from each of said passage-

ways adapted to conduct the discharge of water and aggregates therethrough to a point adjacent the level of the highest interior point within said compartment.

2. A grading device comprising a compartment adapted to receive aggregates and water under pressure, said compartment being divided into superposed passageways, an inlet port located in the uppermost of said passageways, screening elements located in the division walls between said passageways, and separate outlet conduits leading from each of said passageways adapted to conduct the discharge of water and aggregates therethrough to a point adjacent the level of the highest point within said compartment and extending from thence to the desired point for the discharge of the materials carried by each conduit.

3. A grading device comprising a compartment for the reception of a mixture of water and aggregates, said compartment being divided into superposed passageways, an inlet port located in the uppermost of said passageways, screening elements located in the division walls between said passageways, and separate outlet conduits leading from each of said passageways whereby the water level within said compartment is maintained above the level of the highest point of said screening elements.

4. A grading device comprising a compartment for the reception of a mixture of water and aggregates, said compartment being divided into superposed passageways, an inlet port located in the uppermost of said passageways; screening elements located in the division walls between said passageways, separate outlet conduits leading from each of said passageways, and means for controlling the discharge from said compartment so as to maintain the water level within said compartment above the highest point of said screening elements.

5. A grading mechanism comprising a compartment for the reception of a mixture of water and aggregates, said compartment being divided into superposed passageways, an inlet port located in the uppermost of said passageways, screening elements located in the division walls between said passageways, separate outlet ports leading from each of said passageways, and means for controlling the flow through and discharge from said passageways so as to maintain the water within said compartment at a desired velocity of flow and level.

6. A mechanism for grading aggregates comprising a conduit through which aggregates and water are adapted to be pumped under pressure, a compartment of larger sectional capacity than the first portion of said conduit interposed in and forming a portion thereof which compartment reduces the rate of flow of materials therethrough so

as to permit the gravitation thereof, grading elements disposed within said compartment and discharge conduits of lesser combined capacity than said compartment whereby the rate of flow through said discharge conduits is increased to a point to carry said aggregate.

Signed at Chicago, county of Cook and State of Illinois, this 21st day of January, 1919.

LESLIE W. BEAVEN.
